UNITED STATES PATENT OFFICE

WILHELM PETER, OF EDENKOBEN, PFALZ, GERMANY

DEVICE FOR PASSING CABLES THROUGH THE ROOFS OF BUILDINGS

Application filed November 20, 1929, Serial No. 408,651, and in Germany February 2, 1928.

The present invention relates to a novel and suitable device for passing cables and other suitable electrical current conducting means through roofs of any suitable type. Such arrangements may be referred to as roof inserting standards. In the known forms of construction they consist of a roof stand pipe and a socket seated therein and overlapping the end of the pipe, on which a socket there, is extremely unsatisfactory as regards penetration of water and moisture, prevention of short circuits and the occurrence of fires both in the device itself and in buildings.

The present invention eliminates these disadvantages in that the current conducting members such as wire leads and cables, and auxiliary elements such as pipes and the like, passed through the socket and roof stand pipe, and are held securely and packed by screw connections so that even in the case of destruction of the hood water and moisture cannot penetrate. The water and airtight closure at the foot of the standpipe prevents acid containing vapours and other gases from penetrating from the interior of the building, for example, from chemical factories and the like. The entire construction of the device and of the separate parts thereof and of the screw connections enable not only the production but also the assemblage of the roof standard to be effected in the workshop so that this can be manufactured carefully in the factory and brought to the site of use as a unit and secured to the roof. In this manner there is also obtained a far reaching independency of skill and practice on the part of the erector, which would otherwise be necessary and as regards testing it affords the possibility of thorough testing in respect of fluid tightness and impenetrability of the conductors located in the standard.

For elucidating the invention it will now be described with reference to two examples of

construction illustrated in the accompanying drawings wherein:

Fig. 1 shows a roof standard in section in which the conducting members are separate wires, whilst in the section shown in Fig. 2 the conducting members are formed by cables or cable-like bodies.

The head of the standard consists in the known manner of the protecting hood *a* and its socket *b*. The latter is provided with holes for the passage of the current conductors *g* and with recesses for the reception of a current distributor *f* to which are connected supply leads *e* passing through the open. The socket is provided with a groove-shaped recess by means of which it engages, preferably with the inter-position of a packing *c*, over the upper edge of the stand pipe *d*. For disposing the separate wires *g* according to Fig. 1 there is provided a pipe *h*, preferably an armoured steel pipe, having a screw thread on which are screwed, with the interposition of packing, the securing nut *n* and the lock nut *i*, whereby the pipe *h* and the wires *g* are held firmly in a fluid tight manner at the upper end of the standard.

At the lower end of the standard the pipe *h* is provided for the same purpose with a screw thread for the reception of a conical nut *k*. A closure plate *t* bears at *s* against the lower edge of the pipe *d* so that when tightening the nut *k* the cone *r* presses the ring *w* against the inner wall of the pipe *g* and a fluid tight metal connection is obtained which forms a fireproof closure at the bottom.

The lower screw connection serves simultaneously for securing the fuse box *m* of the building. This box is fitted with its opening *l* over the suitably shouldered nut *k* and secured by the nut *x*.

In the form of construction in Fig. 2 a conventional roof line is shown at *d'*. The conducting element forms the cable *g*. It is also possible to use cable-like conductors. 90

Instead of the pipe h , which extends throughout, there is provided at the upper part a short screw threaded pipe h secured in the socket b by means of the nut n , the two conical bodies o and the pressure ring w . A further reduced screw threaded sleeve p presses the correspondingly reduced portion of the pipe h which is preferably slit, against the covering of the cable which is secured in this manner. At the same time the conductor wires are relieved of pull. The screw connection at the lower portion of the pipe a is effected in the manner shown in Fig. 1. As however the pipe h is omitted there is again provided a screw threaded pipe h^1 on which is fitted the conical nut r , the lock nut k and a closure plate t . By tightening the nut k the pressure ring w is pressed by the conical portion of the nuts r and t against the inner wall of the pipe d . The closure disc t is also adapted to take up the axial thrust of the stand pipe d . This is secured by an angle iron u and a tubular bell v to the upper side of a roof beam of a roof d' on the upper side thereof. The supporting plate t engages under the edge s of the stand pipe d and at the same time is connected by a projection with a corresponding slot in the angle iron u . The inner supporting ring w prevents the standpipe d from being deformed or crushed when tightly drawing up the tubular bell v . For increasing the fireproofness the free space of the pipe d may be fitted with a fireproof mass for example kieselguhr z . It will be understood that modifications may be made in the details of construction without departing from the scope of the invention.

What I claim is:

1. Means for supporting electrical cables with respect to roofs and the like including a bracket carried by a roof element, a stand pipe carried by the bracket and rising above the roof, a hood resting on and having seal connection with the upper end of the stand pipe, a conductor pipe for the electrical cables extending longitudinally of the stand pipe and into the hood, means on the upper end of the conductor pipe to seal the same, means carried by the conductor pipe to interlock the conductor pipe and hood against relative movement in one direction, means on the lower end of the conductor pipe whereby the latter may be connected to a junction box, and means cooperating with the conductor pipe and with the stand pipe to seal the lower end of the latter.
2. Means for supporting electrical cables with respect to roofs and the like including a bracket carried by a roof element, a conductor pipe removably connected to a junction box and extending through and above the bracket, a hood interlocked with the upper end of the conductor pipe, means whereby the upper end of the conductor pipe may be sealed within the hood, a stand pipe

encircling the conductor pipe and supported by the bracket, the upper end of the stand pipe having seal connection with and supporting the hood, sealing means for the lower end of the stand pipe, said sealing means being carried by the conductor pipe, and means for insuring cooperation of the sealing means with the conductor pipe to seal the interior of the latter at the lower end against the elements.

In testimony whereof I affix my signature.
WILHELM PETER, W. I.
